SUSPENDED FLOWER POT

Michael Neels, 3046 Marna Ave.,
Long Beach, Calif. 90808

Filed Sept. 13, 1971, Ser. No. 180,253

Term of patent 14 years

Int. Cl. D11—02
U.S. Cl. D35—3 A

FIG. 3

FIG. 4

FIG. 1 is a perspective view of a suspended flower pot showing my new design, it being understood that the chain links interconnect along the length of the hanging support.

FIG. 2 is an enlarged partial perspective view of the decorative links exemplar shown in FIG. 1.

FIG. 3 is an enlarged partial side elevation of the suspended flower pot shown in FIG. 1.

FIG. 4 is an enlarged partial plan view of the suspended flower pot shown in FIG. 1.

I claim:

The ornamental design for a suspended flower pot, substantially as shown and described.
